UNITED STATES PATENT OFFICE.

JOEL C. WELLS, OF SOUTHBRIIDGE, MASSACHUSETTS.

SPECTACLES.

1,241,690.

Specification of Letters Patent.

Patented Oct. 2, 1917.

Application filed December 18, 1913. Serial No. 807,482.

To all whom it may concern:

Be it known that I, JOEL C. WELLS, a citizen of the United States, residing at Southbridge, in the county of Worcester and State 5 of Massachusetts, have invented certain new and useful Improvements in Spectacles, of which the following is a specification.

My invention relates to improvements in spectacles and has particular reference to an 10 improved type of mounting wherein the weight is carried on the nose by fixed supports located substantially in the line of the lenses and capable of ready adjustment to the facial requirements of the wearer, and 15 which is held from toppling by independent anchoring means.

The leading object of my invention is the provision of a novel, attractive and commercially practical construction of the character 20 above mentioned.

Among other objects of my invention are the provision of an improved mounting of this type in which the various parts shall be 25 detachably connected and of standard construction to permit of removal, replacement and interchangeability of the parts, as desired; the provision of adjusting means whereby the supports and the anchoring means may be easily conformed to the facial 30 requirements of the wearer, and a simplification of construction whereby the various parts may be accommodated in minimum space and present the most attractive appearance.

Further objects and advantages of my improvement should be readily apparent by reference to the following specification taken 35 in connection with the accompanying drawings forming a part thereof, and it will be understood that I may make any modifications 40 in the specific details of construction shown and described within the scope of the appended claims without departing from or exceeding the spirit of my invention.

Figure I represents a front view of one 45 form of my invention.

Fig. II represents a sectional view as on the line II-II of Fig. I.

Fig. III represents a fragmentary per-

spective rear view of the construction illustrated in Fig. II.

Fig. IV represents a view similar to Fig. II of a slightly modified construction.

Fig. V represents a perspective view of another modification.

Fig. VI represents a perspective view of the parts of my mounting in disassembled relation.

In the drawings, in which similar characters of reference are employed to denote corresponding parts throughout the several views, the numeral 1 designates the lenses secured within the clips 2 carried by the bridge 3, by screws or other customary lens securing means 5.

In Figs. I, II and III, I have shown the bridge 3 as provided with the seat 4 for swinging movement of the guard arm or lever 15, which bears the upper pad 17, the lever being actuated as by the spring 19, 70 while depending from the bridge at or adjacent its seat is the lower weight supporting or bearing guard 7, having rising therefrom the spring arm 24, so positioned as to be engaged by the lever 15 on rearward or opening movement of the lever, the lever thus serving to cam or spring back the upper pad 23 carried by this spring arm, the lever being provided with the customary fingerpiece 14 for actuation thereof.

In Fig. IV, I have shown a slightly modified lower guard comprising the weight supporting member 7 and the supplemental forwardly extending weight supporting portion 22 to aid in more correctly balancing the 85 mounting on the nose, the pads or bearing members 7 and 22 being independently adjustable to exactly fit the sides of the nose of the wearer.

Fig. V illustrates a further modification, 90 in which the lower member 7 has rising therefrom the looped arm 25, having its loop so disposed that the lever will swing into the loop without disturbing the upper pad 23.

In the use of any of the foregoing forms 95 of my invention as illustrated and described, the general fitting and operation of the same are identical, that is, the guards 7

are adjusted to properly fit against the nose of the wearer and steady the mounting in position, it being understood that they may be so adjusted as to support the entire 5 weight of the mounting or as to support but a part of said weight, the remainder if desired may be supported by the bridge which may be adjusted to exactly fit the crest of the nose, as may be deemed most advantageous 10 by the fitter of the mounting. In any event, the bridge and lower bearing member or members, as the case may be, support the entire weight of the mounting, and on account of the position of the lower weight 15 bearing member, in advance of the plane of the lenses, the mounting, when properly adjusted, should be balanced upon the face so as to steady it in place without the use of any supplemental anchoring devices when 20 the head is held erect. This adjustment of the lower guard is attained by bending in and out, sidewise, or torsional twisting of the bearing blade or parts thereof, and of the reduced neck 20 provided for this purpose, the competent adjuster bending these 25 various ductile parts until the exact fit is attained.

The parts are made sufficiently pliable to permit of this adjustment, and at the 30 same time are rigid enough to retain the adjustment under ordinary service conditions. The advantage of this should be readily apparent, as it will be seen that the mounting when fitted will fit at but one 35 point on the nose, and thus the wearer is sure at all times of getting the mounting in exactly the right position on his face, a result difficult of attainment hitherto in the use of glasses held on the nose by 40 spring pressed clamps or the like, and a result, the importance of which cannot be over-estimated, particularly in astigmatic or other similar eye troubles.

The mounting having been properly fitted, as above pointed out, the next step is the correct adjustment of the supplemental anchoring devices so that the same will fit into the socket at the junction of the nose and eyebrows and will so engage the flesh 50 and loose skin at this point as to hold the mounting against any rolling or tilting forward and falling off the face, this being the natural loosening movement of a properly adjusted mounting.

To prevent this movement the upper guard arm is then adjusted by bending of the loop therein, by twisting of the offset 16 thereof, or the like, the idea being to secure the best possible engagement of the pad or 60 anchoring member 17 with the nose, that is to say, the engagement where this pad will best fit into the aforementioned socket and engage the loose flesh to grip the same with a minimum of spring pressure, a loose

pad being preferably employed for this purpose, as it will better bite into the flesh and resist forward tilting or rolling movement, although an ordinary rigid pad may be employed if preferred by the particular wearer or fitter of the mounting.

From the foregoing description taken in connection with the accompanying drawings, the construction of my improved mounting should be readily apparent, and it will be seen that I have provided a novel construction of this character in which the lower guard 7 may be readily adjusted to fit the side of the nose and bear most of the weight of the mounting, while the upper or supplemental guard member, which is preferably disposed somewhat rearwardly of the first mentioned guard member, serves to grip the flesh at the upper part of the nose and anchor the mounting against tilting movement, and consequently I have provided an extremely satisfactory, adjustable and practical construction which may be readily assembled, in which the various parts are interchangeable, and which should prove extremely efficient for the desired purpose.

I claim—

1. In an ophthalmic mounting, the combination with a support, of a resilient non-pivoted pad carried thereby, a pad arm pivoted to the support, means for actuating said pad, the relationship of the pads being such that the pivoted pad arm will contact with and spring the resilient pad outwardly upon actuation of the arm about its pivot, substantially as and for the purpose described.

2. In an ophthalmic mounting, the combination with a support, of a resilient upper bearing pad carried thereby, a main pad arm pivotally secured to the support, means for manually actuating the arm in one direction and for resiliently actuating it in the opposite direction, the support for the resilient pad extending transversely of the plane of movement of the pivoted arm, and the relative adjustment of the parts being such that the arm will contact with the resilient pad support and spring the support outwardly upon manual actuation of the arm.

3. In a spectacle mounting, the combination with a support, of a guard carried thereby, a pad resiliently supported upon said guard for independent movement relative thereto, and a second pad rotatably mounted on said support, said resiliently supported pad being actuated through movement of said second pad.

4. In a spectacle mounting, the combination with a support, of a guard carried thereby, an arm carried by said guard, a pad carried by said arm, and a second pad rotatably mounted on said support, said

arm lying in the path of movement of said second pad.

5. In a spectacle mounting, the combination with a support, of a guard carried thereby, an arm carried by said guard, a pad carried by said arm, and a second pad rotatably mounted on said support, said arm lying in the path of movement of said second pad, means to automatically actuate

said second pad in one direction, and means 10 for manually actuating the same in the other direction.

In testimony whereof I affix my signature in presence of two witnesses.

JOEL C. WELLS.
